UNITED STATES PATENT OFFICE.

RICHARD RABY, OF YORK, PENNSYLVANIA, ASSIGNOR TO THOMAS J. YOUNG, EDWARD T. BENTZ, AND DAVID A. MINNICH, OF YORK, PENNSYLVANIA.

THILL-CO尤LING AND SHAFT-SUPPORT.

SPECIFICATION forming part of Letters Patent No. 772,824, dated October 18, 1904.

Application filed April 18, 1904. Serial No. 203,636. (No model.)

To all whom it may concern:

Be it known that I, RICHARD RABY, a citizen of the United States, residing at York, in the county of York and State of Pennsylvania, have invented certain new and useful Improvements in Thill-Couplings and Shaft-Supports, of which the following is a specification, reference being had therein to the accompanying drawings.

10 My invention relates to improvements in thill-couplings and shaft-supports; and one object of my invention is the provision of an ornamental and attractive device which may be easily and inexpensively applied and which 15 will perform the functions of a thill-coupling and shaft-support in an efficient and practical manner.

Another object of my invention is the provision of a combined thill-coupling and shaft-support which will also serve to prevent rattling or working loose of the parts of the coupling and which by reason of its simplicity and inexpensiveness, efficiency, and practicality will command itself as very useful and 25 desirable.

With these objects in view my invention consists of a combined thill-coupling and shaft-support embodying novel features of construction and combinations of parts, substantially 30 as disclosed herein.

Figure 1 represents a perspective view of my combined thill-coupling and shaft-support. Fig. 2 represents a vertical central sectional view thereof; and Fig. 3 represents a 35 transverse sectional view through the thill-irons, draw-irons, springs, and loop.

In the drawings the letter A designates one of the thills or shafts. B designates the thill-iron secured thereto, and having the head 40 formed with the journals C, which fit in the open bearing D of the draw-iron E, said draw-iron being formed with the angular or shoul-dered portion E and with the plate G, and H designates the clip which connects the axle J 45 with the plate.

Secured to the inner portion of the plate G is the inner end K of the curved spring mem-ber K', which is provided with the forwardly-

projecting spring portion K², formed with the guides or cleat K³ and provided at its end 50 with an opening K⁴, and fitting in said guide or cleat is the inner end of the shaft-supporting spring member L, which carries at its upper end the shaft-supporting hook M and at its lower forward end is provided with an 55 opening N, which aligns with the opening of the other spring member, and passing through said opening is a lug O, formed on the loop or bail P, which has its upper end provided with lugs Q, fitting in the open bearings of 60 the draw-iron and bearing down upon the trunnions or journals C of the thill-iron, thus holding the thill-iron in proper place in the draw-iron and preventing rattling of the parts.

65 From this construction it will be seen that I provide a perfect thill-coupling and shaft-support and that the two spring members serve to suspend the shaft and also in connection with the bail serve to hold the thill-iron 70 in proper position in the draw-iron, and thus my device performs both functions of a thill-coupling and shaft-support in an efficient manner, and that the device is ornamental in appearance, compact, simple, and durable in construction and entirely practical in every respect.

75 Having thus fully described my invention, what I claim as new, and desire to secure by Letters Patent, is—

1. In a combined thill-coupling and shaft-support, the combination of the thill-iron, the draw-iron having the open bearing, the bail having the lugs engaging said bearing, and the spring shaft-support having one end bearing upon said bail and the other end serving to support the shaft.

2. In a combined thill-coupling and shaft-support, the combination of the draw-iron, the spring having the guide and connected to 90 said draw-iron, the spring shaft-support fitting in said guide, the thill-iron fitting in the draw-iron and the bail connecting the thill-iron bearing and the thill or shaft support.

3. The combination of the shaft, the thill-iron having the journals, the draw-iron hav-

ing the open bearings to receive said journal, the bail having the lugs fitting in said open bearing and resting upon the journals of the thill-iron, and the double-spring thill or shaft 5 supporting device connected with the draw-iron and bail at one end and having the thill or shaft supporting device at its other end.

4. The combination with the axle, the thill-iron and draw-iron, the spring member having its upper end connected with the draw-iron, the spring shaft-support connected to the lower end of said spring member and having its upper end adapted to support the shaft.

5. The combination with the axle, the thill-iron, the thill-iron bearing in the draw-iron, the bail having its upper end bearing upon the thill-iron, and the spring connection between the draw-iron and the bail and the shaft-support having its lower end bearing upon 20 the bail and its upper end adapted to support the shaft.

6. The combination with the axle, the draw-iron having the open bearing, the thill-iron having the journals fitting in said open bearing, the bail having the lugs resting on said 25 journals, and the shaft-support holding said

bail in position and serving to support the shaft.

7. The combination with the axle, the draw-iron, the thill-iron, the spring member connected to the draw-iron and having its free portion provided with a guide, and the shaft-support having its lower end fitted in said guide and its upper end carrying means for supporting the shaft. 35

8. The combination with the axle, the thill-iron, the draw-iron, the spring member connected to the draw-iron and having an opening in its lower end, the shaft-supporting spring carrying means at its upper end to support the shaft, and having an opening in its lower end in line with the opening of said spring member, the bail having the lugs fitting in said opening and having the lugs on its upper end to engage and retain the thill- 45 iron in position.

In testimony whereof I affix my signature in presence of two witnesses.

RICHARD RABY.
